MIXING AND DISPENSING FAUCET

Filed May 11, 1953

UNITED STATES PATENT OFFICE

170,953

MIXING AND DISPENSING FAUCET

Anthony Turak, Cleveland, Ohio

Application May 11, 1953, Serial No. 24,959

Term of patent 14 years

(Cl. D2—3)

To all whom it may concern:

Be it known that I, Anthony Turak, a citizen of the United States, residing in the city of Cleveland, county of Cuyahoga, and State of Ohio, have invented a new, original, and ornamental Design for a Mixing and Dispensing Faucet, of which the following is a specification, reference being had to the accompanying drawing, forming a part hereof.

I claim:

The ornamental design for a mixing and dispensing faucet, as shown.

ANTHONY TURAK.
